VACUUM CLEANER HANDLE OR SIMILAR ARTICLE

Gerard J. McLane, Morris Plains, N.J., assignor to Air Reduction Company, Incorporated, New York, N.Y., a corporation of New York

Filed Mar. 8, 1968, Ser. No. 10,902

Term of patent 14 years

(Cl. D49—17.2)

FIG. 1

FIG. 3

FIG. 1 is a side elevational view of a vacuum cleaner handle or similar article showing my design, the opposite side of the handle having the same overall appearance; FIG. 2 is a top plan view thereof; FIG. 3 is a bottom plan view thereof.
I claim:

An ornamental design for a vacuum cleaner handle or similar article, as shown and described.
